United States Patent Office

Des. 183,337
Patented Aug. 5, 1958

183,337

THERMOSTAT OR SIMILAR ARTICLE

Paul Wrablica, Jr., Corona, N. Y., assignor to Metals & Controls Corporation, Attleboro, Mass., a corporation of Massachusetts

Application October 29, 1957, Serial No. 48,269

Term of patent 14 years

(Cl. D26—13)

Fig. 1.

Fig. 3.

Fig. 2.

Fig. 1 is a top perspective view of a thermostat or similar article, showing my new design;

Fig. 2 is a bottom perspective view; and

Fig. 3 is a rear perspective view thereof.

The dominant features of my new design are shown in solid lines in the drawing, the broken-line showing of a portion of the article being omitted from Figs. 1 and 2 for convenience in illustration.

I claim:

The ornamental design for a thermostat or similar article, substantially as shown and described.
